E. T. BENNINGTON
APPARATUS FOR HANDLING ANNUAL BODIES SUCH AS
COILS OF METAL WIRE, ROD, OR STRIP
Filed July 5, 1924

Filed July 5, 1924

UNITED STATES PATENT OFFICE.

EARL T. BENNINGTON, OF CLEVELAND, OHIO.

APPARATUS FOR HANDLING ANNULAR BODIES SUCH AS COILS OF METAL WIRE,
ROD, OR STRIP.

Application filed July 5, 1924. Serial No. 724,219.

To all whom it may concern:

Be it known that I, EARL T. BENNINGTON, a citizen of the United States, residing at Cleveland, in the county of Cuyahoga and 5 State of Ohio, have invented a certain new and useful Improvement in Apparatus for Handling Annular Bodies Such as Coils of Metal Wire, Rod, or Strip, of which the following is a full, clear, and exact description.

This invention relates to an apparatus of the overhead carrier type adapted particularly for picking up and transporting round bundles of wire or rod, gear blanks, tile and 15 other cylindrical or hollow products. The devices used heretofore for transporting bundles of wire or rod in a mill, or from one mill to another have been unsatisfactory as the hooks on which the bundles were intended 20 to be supported were suspended from a single hoist, with the result that the load had to be evenly applied to prevent the accidental discharge of the load or to permit the load to be discharged without difficulty at 25 the discharge point. Furthermore, with the hooks utilized heretofore, difficulties were encountered in applying a load to the hook.

The principal object of the present invention is to provide a carrier adapted particularly for the purpose stated above, which is so arranged, constructed and operated that the operator in the cab of the carrier or on the ground, can readily manipulate the hook so as to pick up one or any number of bundles 30 of wire, rod or other devices, and readily discharge the load after it has been transported to the desired point. In other words, it is the chief aim of the invention to provide a carrier which is efficient, which 35 will reduce the labor heretofore required in handling articles of the nature stated, and will permit the latter to be picked up, transported and discharged without necessity of their being handled manually.

40 In carrying out my invention I utilize a hook which is preferably substantially U-shaped, and is suspended, preferably at opposite ends by two independently controlled hoist drums, which although perhaps capable 45 of being operated from one hoist, preferably from parts of two separate hoists. In the preferred embodiment, these hoists are on separate carriers which can be driven

along the trackway by separate motors connected to a single controller.

55 The invention may be further briefly summarized as consisting in certain novel combinations and arrangements of parts which will be described in the specification and set forth in the appended claims.

60 In the accompanying sheet of drawings, Fig. 1 is a side elevation of a carrier embodying my invention; Fig. 2 is a top plan view of the hook; Fig. 3 is an enlarged cross-sectional view substantially along the 65 line 3-3 of Fig. 1 looking in the direction indicated by the arrow; and Fig. 4 is a transverse sectional view through the lower leg of the hook substantially along the line 70 4-4 of Fig. 1 looking in the direction indicated by the arrow.

75 The hook upon which the load is supported is preferably U-shaped, and is composed of upper and lower legs 10 and 11 which are parallel, and a head 12 connecting the legs at one end of the hook. The lower leg 11 is the part which received the load, which is indicated as being in the form of bundles 80 of wire or rod 13. The upper leg is in the form of a beam which can be constructed of any suitable structural material, but the lower or load receiving leg 11 is preferably cylindrical in form and may consist of a hollow tube as shown. The free end of the lower leg has a tapered nose 14 in order that 85 the articles can be readily picked up as hereinafter described.

90 The upper leg 10 is provided near opposite ends with two sheaves 15 and 16 adapted to accommodate hoist cables 17. Each sheave is preferably connected to a yoke 18 (see Fig. 3) having a swivel connection with the side members of the upper leg 10, and the housing of each sheave is preferably swiveled at the center of the yoke as indicated at 19 to turn about an axis at right angles to the axis of movement of the yoke 18. With this arrangement each sheave has 95 freedom of movement so that it can accommodate itself naturally to the plane or direction of the cable 17.

100 The hoist cables 17 are adapted to be wound onto and unwound from independently rotatable drums which make it possible not only to raise and lower the hook 105 bodily but to lower one end independently

of the other so as to tilt or tip the hook, as indicated by dotted lines in Fig. 1. This is particularly useful when the hook is taking on a load or discharging a load.

- 5 Assuming that the hook is designed to receive bundles of wire, such as indicated at 13, should the bundles be standing in a row, and in substantially vertical position, the hook can be lowered with the legs substantially horizontal, and then the lower leg can be inserted or run through the bundles. On the other hand, the bundles may be lying flat, or substantially flat on the ground in more or less spaced or scattered relation. 10 In that event the operator will lower the free end of the hook until it assumes the desired angle, and then pick up the bundle by moving the tapered end of the lower leg into the bundle. Likewise, in discharging 15 the load, the operator may, if occasion demands, lower both ends of the hook uniformly or simultaneously until the bundles rest on the ground or other support adapted to receive them, and then back the hook out 20 from the bundles. On the other hand, it may be desirable to simply slide them off the hook, in which event the free end of the hook will be lowered to permit the bundles to slide off by gravity. 25 As already stated, I prefer that the drums form parts of separate and independently controlled hoists. In the present instance the hoists are on two separate carriers 20 and 21 which may be of standard 30 construction. These carriers are preferably both motor driven, the motors and motor drives being indicated conventionally at 22. Standard motor heads and driving means between each motor and the track 35 wheels may be employed, such for example as shown in my prior Patent 1,412,831. The wheels of the carriers engage a suitable overhead track-way which generally is a monorail, which I have indicated at 23, in 40 which event the wheels of the carriers engage flanges on opposite sides of the rail in the customary manner. Both motors will be connected to and controlled by a single controller, (not shown) which in 45 the construction illustrated will be located in the operator's cab 24 which is attached to the carrier 20. In this instance the cab 24 has wheels engaging the rail 23, and the cab has suitable trolley wheels 25 engaging trolley wires 26 which parallel the rail 23, and 50 supply current to the traversing motors and to the two hoist motors.

In Fig. 1 the hoists are indicated generally by the reference character 27, each hoist having a drum 28 which receives one of the hoist cables 17, and an electric motor indicated at 29 for rotating the drum. Standard hoists may be employed on both carriers. The motors of the hoists are controlled through separate switches or con-

trollers, (not shown) in the cab 24. Instead of electric hoists, pneumatic hoists may be employed and in some instances hand operated hoists could be utilized to advantage.

When the controller which is connected to the two traversing motors 22 is operated, both carriers will travel in unison or at the same speed along the track. They are held in more or less definite spaced relation not only by reason of the fact that the two motors operate at the same speed, but also by the pull of the hoist cables due to the weight of the hook, or the hook and its load. I prefer, however, to connect the two carriers 20 and 21 by a flexible or extensible coupling 30 composed of two telescopic parts. The flexible or extensible coupling is useful when the carrier is traveling around a curve, as it permits the ends to separate when the curve is being rounded, and reduces the wear of the carrier wheels on the rail 23.

It will be seen, therefore, that I have provided a carrier with a load hook supported in a manner such as to admit of bundles of wire or other articles being picked up, transported and discharged without requiring that the articles be handled manually. It has been found in practice that wire bundles can be picked up, transported and discharged easily and rapidly and it is a simple matter for the operator to cause the hook to pick up the bundles and also to discharge the bundles in just the desired position.

It will be understood, of course, that my improved carrier may be employed but transporting articles or loads other than bundles of wire or rod. It is to be understood also, that my invention in its broad aspects may be put in practice in different ways or by different instrumentalities. For example, I do not regard it essential to my invention that the hoists be located on two separate carriers, or if two carriers are employed, that they both be motor driven, or that two wholly independent hoists be employed. Furthermore the load hook and the hoists or hoist drums may be employed on a carrier of a different type than here illustrated, as for example on the bridge or boom of a crane, or on a carrier which is hand propelled, or the hoists may be controlled or operated from the ground.

I therefore aim in my claims to cover all modifications which do not involve a departure from the spirit and scope of my invention as defined in the appended claims.

Having described my invention, I claim:

1. Apparatus for handling annular bodies such as coils of metal wire rod or strip comprising an overhead traveling support, a substantially U-shaped hook having an upper leg and a single load carrying prong

below the same adapted to extend through a plurality of coils or similar annular bodies, and means for supporting the hook from the traveling support and for holding the same against tilting comprising a pair of flexible hoist elements extending upwardly in the plane of the hook to the traveling support, one from the rear end of the hook and the other from the forward end of the upper leg thereof.

2. Apparatus for handling annular bodies such as coils of metal wire rod or strip comprising an overhead traveling support, a substantially U-shaped hook having an upper leg and a single load carrying prong below the same adapted to extend through a plurality of coils or similar annular bodies, and means for suspending said hook from the traveling support comprising a pair of hoist cables one connected to the rear end of the hook and the other to the forward end of the upper leg thereof and independently controlled drums for operating said cables whereby the hook may be tilted to retain a load of annular bodies on the prong or to discharge the load from the prong.

3. Apparatus for handling annular bodies such as coils of metal wire rod or strip comprising an overhead traveling support, a substantially U-shaped hook having an upper leg and a single load carrying prong below the same adapted to extend through a plurality of coils or similar annular bodies, sheaves swiveled to the hook adjacent opposite ends thereof, the forward sheave being swiveled to the upper leg, and independently operable hoist cables suspended from the traveling support and having loops in which the sheaves are supported.

4. Apparatus for handling annular bodies such as rod wire or strip coils comprising an overhead traveling support, a substantially U-shaped hook having an upper leg and a single load carrying prong below the same, sheaves at opposite ends of said upper leg, said sheaves being swiveled to the leg by means permitting the sheave to swing about either of two axes, one transverse with respect to said leg and the other at right angles to said first-mentioned axis, and independently operable hoist cables suspended

from the traveling support and having loops in which the sheaves are supported. 55

5. In a load carrier, an overhead traveling support having independently controlled hoist drums, a U-shaped load supporting hook having an upper leg formed of a pair of spaced parallel bars and a lower leg comprising a single bar rigidly connected at its rear end to the rear end of the upper leg, sheaves mounted between the bars of the upper leg adjacent the front and rear ends thereof, and a pair of looped hoist cables each connected at one end to the said support and at the other to one of said drums, each sheave being supported in the loop of one of said cables. 60 65

6. In a load carrier, an overhead traveling support having independently controlled hoist drums, a U-shaped load supporting hook having an upper leg and a lower leg joined at its rear end to the rear end of said upper leg, transverse yokes carried by the upper leg and swiveled to turn on horizontal axes, sheave cases swiveled to said yokes to turn about vertical axes, sheaves journaled in said cases, and cables extending from said drums around the under sides of the sheaves and upwardly to the said support and attached thereto. 70 75

7. In combination, a pair of carriers mounted to travel one in advance of the other on an overhead track and connected by a flexible coupling, each carrier having a hoist with a cable drum, a substantially U-shaped load supporting hook, and cables engaging said drums and connected to opposite ends of said hook. 80 85 90

8. In combination, a pair of overhead traveling carriers provided with propelling motors adapted to be simultaneously controlled, said carriers being mounted to travel one in advance of the other on an overhead track and connected by a flexible coupling, hoists carried by said carriers and adapted to be independently operated, a U-shaped load supporting hook having upper and lower legs, and cables connecting opposite ends of the upper leg of the hook to the two hoists. 95 100

In testimony whereof, I hereunto affix my signature.

EARL T. BENNINGTON.
